ATTYS.

UNITED STATES PATENT OFFICE.

HARRY M. PFLAGER, OF ST. LOUIS, MISSOURI, ASSIGNOR TO COMMONWEALTH STEEL COMPANY, OF ST. LOUIS, MISSOURI, A CORPORATION OF NEW JERSEY.

RAILWAY TRUCK.

Application filed March 19, 1924. Serial No. 700,323.

To all whom it may concern:

Be it known that I, HARRY M. PFLAGER, a citizen of the United States, residing at St. Louis, Missouri, have invented a certain 5 new and useful Improvement in Railway Trucks, of which the following is a specification such as will enable others skilled in the art to which it appertains to make and use the same.

10 My invention relates to railway car trucks and consists in an improved mounting of a swinging bolster.

The object of my invention is to provide 15 pivotal suspension means for a bolster which may be applied to spaced transoms of a truck and will include suspension links between which the bolster is located and means preventing frictional contact of the links and the bolster.

20 This invention is also shown and described in my copending application Serial Number 569,145, filed June 7, 1922, of which the present is a continuation in part.

In the accompanying drawings which 25 illustrate my invention—

Figure 1 is a longitudinal section through a truck containing my invention.

Figure 2 is a transverse section through the truck shown in Figure 1.

30 Figures 3 and 4 illustrate modifications of my invention and are referred to herein-after.

The truck includes the usual wheels 1, 35 axles 2, equalizers 3, and a frame 4 carried by the equalizers through springs 5. The frame includes two horizontally spaced transoms 6 and the upper faces of these transoms are adapted to provide bearings for the ends of pins 7 which span the space 40 between the transoms and from which are pivotally suspended links 8. These links 45 swingingly support the spring plank 9 which carries springs 10 supporting bolster 11 upon which the car body (not shown) is 50 mounted. The top surface of the ends of bolster 11 is below the upper ends of links 8 and below pin 7 and I utilize a rigid member extending between the links of each pair 55 to space the latter transversely of the bolster 60 to such an extent that there will be no engagement between the links and the bolster 65 to chafe either of these members and to interfere with the swinging movement of the 70 bolster.

55 In the preferred construction, this rigid

member is shown as a cylindrical sleeve 12 surrounding pin 7 and preferably secured to the latter either by being tightly fitted thereon or pinned thereto as indicated at 17.

As the ends of pins 7 are held against 60 axial movement by their saddles on the transoms, the links are also held in the position shown and spaced from the transoms as well as the bolster.

In Figure 3 the spacing member consists 65 in a short angle iron 13 removably secured to the pin 14 by means of bolts 15.

In Figure 4 the links are held in predetermined relation to each other by means of 70 cotter pins 16.

With any of these constructions, it will be impossible for the upper ends of the links to approach closer to each other than the distance provided by the spacing member which, however, can be removed for shortening or for the substitution of a longer member or for the removal of the pin from the links if the bolster is to be removed from the truck.

Obviously, the details of my invention 80 may be modified other than as shown, without departing from the spirit of the invention as expressed in the following claims.

I claim:

1. In combination with a truck frame, its 85 wheels and axles, transoms integral with the side members of said truck frame, a bolster arranged between said transoms, swinging links for supporting said bolster, a pin passing through the upper ends of said links and being seated upon said transoms and held against longitudinal movement, and a sleeve secured on said pin for spacing the upper ends of said swinging links from said 90 transoms and bolster.

2. In a car truck, a frame including horizontally spaced members, a pin spanning the space between said members and held against lengthwise movement thereon, links pivotally suspended from said pin, a spring 100 plank swingingly carried by said links, a bolster carried by said spring plank between said links, and means removably secured to said pin for spacing said links apart thereon so as to clear said bolster and members.

In testimony whereof I hereunto affix my signature this 15 day of March, 1924.

H. M. PFLAGER.
